UNITED STATES PATENT OFFICE.

MILTON T. WESTON, OF NEW YORK, N. Y.

RESILIENT WHEEL.

Application filed May 12, 1922. Serial No. 560,325.

To all whom it may concern:

Be it known that I, MILTON T. WESTON, a citizen of the United States, and a resident of New York, in the county of New York and State of New York, have invented a new and useful Improvement in Resilient Wheels, of which the following is a specification.

My invention relates to an improvement in resilient wheels for automobiles and other vehicles wherein the pneumatic resilient member is located in the central part of the wheel in an enlarged enclosed hub casing, thereby being protected from the elements and from contact with the road surface.

Such intermediate resilient members are shown in my Patent No. 1,289,586, December 31, 1918 and in my Patent No. 1,431,610, dated October 10, 1922.

In the present invention an outer shoe is provided to protect an inner expansible and inflatable tube, thus forming a resilient member somewhat like ordinary rubber tires; but with this difference, that in applying such tubes to resilient wheels of the class described herein, certain radical modifications in the conditions are met, that have brought about the invention described herein.

In such resilient wheels, I prefer to make the resilient member of an outer fabric shoe and an inner rubber tube, and I furthermore form the shoe with a number of restricted or contracted sections intermediate to sections that are not contracted for the purpose of obtaining a radical compressibility, as more particularly described in the application referred to above. In such a resilient

tube the inner periphery is subjected to a kneading action on the part of the inner member of the wheel, and therefore, the circumferential opening that is formed in the shoe to admit the inner tube cannot be on the inner periphery.

To meet these conditions the tube and particularly the shoe is made in a novel manner hereinafter more particularly described.

In the accompanying drawings:—

Figure 1 is a view showing the appearance of the inner periphery of the shoe of my improved tube;

Figure 2 is a longitudinal section of the tube along line 2—2 Figure 1;

Figures 3 and 4 are transverse sections of the tube showing respectively the restricted

and the unrestricted portions thereof, taken on lines 3—3 and 4—4 Figure 1; and

Figures 5 and 6 are similar sections of another form that my invention may take.

As shown in my prior Patent No. 1,431,610 above referred to, the tube is made with certain constricted portions as shown at 1 in Figures 1 and 2 with intervening unrestricted portions 2. The undulations thus formed permit the radial compression of the tube without stretching the fabric. To introduce the inner tube it is necessary to part the shoe circumferentially and this I do on the outer periphery and I prefer also to so form the parting edges as to have them overlap.

Figures 3 and 4 show a preferred form for such an overlapping joint which consists of an overlap of one edge 3 over the other edge 4, the inner tube being represented at 5. I prefer further to make an offset as at 6 on the inner side of the outer and on the outer side of the inner lap which, when engaging with each other will lock the two edges together against the expanding stress to which the shoe is subjected when the inflation of the inner tube presses the shoe into close contact with the outer rim member of the wheel.

As shown in Figures 5 and 6 a modification of the invention may consist of a shoe having two edges 15, 15, and an overlapping circumferential strip 6', which strip being made with a slot 7, into which fit the two raised lips 8, on the edges of the shoe, interlock therewith to prevent lateral displacement when pressure is applied within the inner tube.

It is not claimed that such construction of outer shoes would be practical for use as ordinary road contacting tires as the invention herein disclosed is only intended and only adapted for use as an interior or hub cushion.

I have shown the parting of the shoe on the outer periphery as this part is more uniform of contour and is, moreover, less subject to distortion, not having the same kneading action as the interior periphery. In Figure 3 is shown, in outline only, the parts of the resilient wheel which form the casing for holding the pneumatic hub tube described herein. The part 9 is the bearing plate for the hub portion of the wheel. The part 10 is the outside rim or band of the wheel. Parts 11 are the sides and outer

plates or covers of the wheel and part 12 is the tire holding rim. It will be understood from this description in connection with the drawings that the pneumatic tube is flattened axially in such a way that when it is deflated, it is readily moved laterally into and out of position between the outside seat or band 10 and the movable pressure plates 9, these parts being likewise provided with 10 axially flattened contours which require no warping or stretching of the tube for insertion or removal.

For full illustration of the various members of the resilient wheel and the manner 15 in which it operates reference is made to my prior U. S. Patents Nos. 1,289,586 and 1,431,610 referred to above.

I claim:

1. In a resilient wheel, the combination 20 with a pneumatic tube comprising an inner elastic tube and an enveloping flexible shoe, said shoe having restricted and unrestricted portions permitting local distortion on its inner periphery and a circumferential parting on the outer periphery thereof, of a peripheral band bearing on the outer periphery of said shoe.

2. In a resilient wheel, the combination 25 of a pneumatic tube, comprising an inner elastic tube and an enveloping flexible shoe, said pneumatic tube having pressure areas peripherally spaced around its inner periphery to permit local distortion at these points, said shoe being provided with a circumferential parting around its outer periphery and an outside band peripherally embracing and bearing against the parted outer periphery of said shoe.

3. In a resilient wheel, a pneumatic tube 40 for resisting relative displacement between concentrically arranged axle-contacting and tread units, said pneumatic tube comprising an inner tube, and an outer shoe provided with a circumferential parting for the introduction and removal of said inner tube, and having portions of the outer wall thereof distant from said circumferential parting permitting local distortion, and means for seating the outer shoe of the pneumatic tube 45 around the circumferential parting therein.

4. A pneumatic tube comprising an inner tube and an outer shoe, said outer shoe being provided with pressure area portions permitting local distortion and extending 50 around its outer periphery, with a parting therein for the introduction and removal of said inner tube, and means for seating said

pneumatic tube along the parting therein.

5. In a resilient wheel, a pneumatic tube 60 for resisting relative displacement between axial contacting and tread units, said pneumatic tube comprising an inner elastic tube and an outer shoe provided with a peripheral parting having interlocking edges, the outer periphery of said pneumatic tube being adapted to be pressed upon thruout its periphery by said tread unit, and means for articulately connecting said wheel units and having pressure engagement with the inner periphery of said pneumatic tube, said periphery being adapted to be locally distorted on angularly spaced pressure areas by means which articulately connect said units.

6. A pneumatic tube for cushioning the 75 relative movements between relatively movable axle-contacting and tread units of a resilient wheel, said pneumatic tube comprising an inner tube and an outer shoe therefor, said shoe being provided with a 80 parting line extending circumferentially along the outside periphery of said shoe, said pneumatic tube being provided with pressure areas presented inwardly at spaced intervals along the inner periphery of said 85 tire, and with constricted neck portions arranged intermediately to said pressure areas, said constricted neck portions being adapted to lock the pneumatic tube to one of said wheel units and said pressure areas being 90 adapted to oppose the relative movements between said wheel units.

7. The combination with a pneumatic 95 tube for resilient wheels, said pneumatic tube comprising an inner tube and outer shoe therefor provided with axially flattened inner and outer peripheral walls and said shoe being provided with a circumferential parting in one of said axially flattened peripheral walls to permit the introduction and removal of said inner tube, of an axially flattened circumferential band 100 extending entirely around the circumference of the axially flattened wall containing said parting, and axially flattened means movably engaging the other axially flattened wall of said pneumatic tube, said pneumatic tube in deflated condition being thereby adapted to be moved by a simple axial movement into and out of position to oppose the 105 movement of said axially flattened means when said pneumatic tube is inflated.

MILTON T. WESTON.
